CLAIM

We claim the ornamental design for a housing for LED board, as shown and described.

DESCRIPTION

FIG. 1 is a front top perspective view of the housing for LED board, showing our new design;

FIG. 2 is a top view thereof;

FIG. 3 is a front view thereof;

FIG. 4 is a rear view thereof;

FIG. 5 is a left side view thereof;

FIG. 6 is a right side view thereof; and,

FIG. 7 is a bottom view thereof.

The broken lines in FIG. 7 are for showing the bottom side of the housing and form no part of the claimed design.
